(57) CLAIM

I claim, the ornamental design for temporary tattoo covers, as shown and described.

DESCRIPTION

This application contains subject matter similar to that disclosed in U.S. application Ser. No. 11/121,253, which was filed May 3, 2005, and is hereby incorporated by reference in its entirety.

FIG. 1 is a top plan view of an embodiment of a temporary tattoo cover design showing a plurality of temporary tattoo covers on a carrier strip;

FIG. 2 is a left side elevational view of the temporary tattoo cover design of FIG. 1, the right side elevational view is identical to FIG. 2; and,

FIG. 3 is a front elevational view of the temporary tattoo cover design of FIG. 1, the back elevational view is identical to FIG. 3.
